International Search Report and Written Opinion for International Application No. PCT/US2020/025371 dated Jun. 12, 2020.

Primary Examiner — Charles D Hanson*(74) Attorney, Agent, or Firm* — Stephen J. Kenny; Vincenzo DiMonaco; Foley Hoag LLP(57) **CLAIM**

The ornamental design for walker apparatus, as shown and described.

DESCRIPTION

FIG. 1 is a front perspective view of the walker apparatus showing my new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof; and,

FIG. 8 is a front perspective view of the walker apparatus of FIG. 1, shown in a folded configuration.
